UNITED STATES PATENT OFFICE.

FREDERICK BALDT, OF CHESTER, PENNSYLVANIA.

DEVICE FOR MOLDING PROPELLER-WHEELS.

SPECIFICATION forming part of Letters Patent No. 627,794, dated June 27, 1899.

Application filed February 1, 1899. Serial No. 704,119. (No model.)

To all whom it may concern:

Be it known that I, FREDERICK BALDT, a citizen of the United States, residing at Chester, in the county of Delaware, State of Pennsylvania, have invented a new and useful Improvement in Devices for Molding Propeller-Wheels, which improvement is fully set forth in the following specification and accompanying drawings.

- 10 This invention consists of a device for molding propeller-wheels, and comprises an angle frame or pattern-support adapted for use in connection with a plurality of flasks, so that after the pattern of a blade and a portion of the hub is secured in position within the frame corresponding molds may be made in a plurality of flasks, the number corresponding to the number of blades in the propeller to be cast. For instance, in a four-bladed 15 propeller the angle of the sides of the frame and the ends of the flask would be ninety degrees, and four of these flasks could be juxtaposed to form the mold for the complete propeller.
- 20 The object of the invention is to provide an angle frame and flask that are adapted for patterns of varying size or in which the pitch or contour of the blade varies, so that propellers of varying size and shape may be cast in 25 molds made thereby.

The invention further consists in the details of construction hereinafter fully described and specifically claimed.

Figure 1 represents a top plan view of a molding device constructed in accordance with this invention. Fig. 2 represents a side elevation thereof. Fig. 3 represents a front end elevation. Fig. 3^x represents a detailed section taken on line *x x*, Fig. 3. Fig. 4 represents a perspective view of a flask removed from the frame. Fig. 5 represents an end elevation thereof. Fig. 6 represents a plan view of the drag or lower section of a flask. Fig. 7 represents a bottom plan view of the hub or upper section of the flask. Fig. 8 represents a perspective view of the frame with the flask removed, the view being taken from the rear side and with the pattern in place. Fig. 9 represents a fragmentary top plan view 45 of the pattern-support and adjacent parts, partly in section. Fig. 10 represents a plan

or fall of the drags in all sections of the molds assembled.

Similar letters and numerals of reference indicate corresponding parts in the figures. 55

In accordance with the principle of this invention I propose to construct a molding device that consists, essentially, of a frame having a pattern-support for holding the pattern of a blade and a portion of the hub so that a plurality of flasks may be applied to have molds formed therein which can afterward be assembled. In the particular embodiment illustrated the device is shown as adapted for casting a four-bladed propeller—that is to 60 say, the sides of the frame carrying the pattern-holder are at an angle of ninety degrees and the open end of the flask is adapted to fit and to be secured firmly against these angular sides of the frame. In this way it is 65 seen that the ends of the mold of the flask being at this angle can be assembled, as shown in Fig. 10, to form the complete mold. The device is also adapted for use in connection with blades that vary in size and shape, 70 whereby the same flask may be used for propellers of different sizes or shapes and which also avoids the necessity of changing or re-baring the flasks. 75

Referring to the drawings, A designates the 80 frame, and B the flask. The frame consists, essentially, of a pattern support or plate 1, the angular side pieces 2, and the bottom piece or base 3. In the construction illustrated the upright portion of the frame is situated transversely at one end of the bottom piece or base, as best shown in Figs. 1 and 2, and consists of the top and bottom cross-pieces 4, the side pieces 2, and the pattern support or plate 1, the latter being situated 85 centrally between and supported by said cross-pieces 4. These parts are suitably connected and braced by the uprights 5 and horizontal braces 6, as found convenient. As shown in Figs. 1 and 8, the side pieces 2 are 90 situated at an angle of ninety degrees and meet against the rear face of the cross-pieces 4, while the pattern-support is situated centrally relative to the meeting ends of the side pieces. The said pattern support or plate 1 95 is mounted to swing between said cross-pieces 4 by means of pivots 6, Fig. 3^x, carried by 100

plates 7 at its upper and lower edges, said pivots being situated within sockets or plates 8 upon the adjacent edges of the cross-pieces. Besides swinging on these pivots the said pattern-support 1 can be shifted laterally, owing to the connection between the plates 8 and the cross-pieces, the same consisting conveniently of slots 9 in the plates, through which pass bolts or other fastening devices 10. To hold the pattern-support 1 rigidly in its adjusted position, I preferably employ the pivoted screw-rods 11, mounted upon one of the uprights 5, which are adapted to enter the bifurcated ends of arms and to hold the pattern-support rigidly in its adjusted position in an obvious manner.

The pattern 14, (best shown in Figs. 1, 8, and 9,) is suitably secured to the inner face of the support or plate 1, its hub portion 15 projecting between the inner ends of the side pieces 2. Although in the drawings I have shown the side pieces as being adjustable or provided with shutters to meet the hub portion of the pattern and also to act in conjunction with the adjustable pattern-support to make a close joint around said hub portion when the mold is being formed, yet it is understood that in accordance with the principle of this invention said side pieces may have suitable openings therein, in which the hub portion 15 fits sufficiently close to allow the sand to be packed to form the mold and to allow said pattern to be removed with the flask, as described hereinafter. In the particular construction illustrated, however, said side pieces are provided with movable sections or shutters 16, Fig. 8, about the same height as the pattern-support. These shutters 16 slide longitudinally in suitable guides, and their inner ends, notched or cut away, as shown at 17, fit over the hub portion of the pattern when the mold is being formed. These sliding and movable shutters 16 not only serve to fit the semicircular hub portion of the pattern to form a close joint and to also allow said pattern to be withdrawn with the flask—that is to say, by withdrawing the shutters, as shown in Fig. 8—but also permit the shifting of the pattern-support and pattern, as above referred to. In connection with certain patterns it is necessary sometimes to turn the pattern-support on its pivot and to shift the same, and in this case the movable shutter or section of the side pieces conforms to the position of the hub portion of the pattern to make a close joint, as shown, or it may be necessary to build up or patch the inner ends of these shutters with strips or the like to make them conform to the shape of the hub.

The flasks (best seen in Figs. 4, 5, 6, and 7) consist of the lower section or drag 18 and the upper section or cope 19, parting obliquely, owing to the pitch of the plate, and having angular open ends to fit between the side pieces of the frame. The drag 18 has the bottom piece 20 provided with the right-angled end portion 21 to fit the side pieces and

to hold the flask in the determined position, and the edges of the drag and cope are beveled at the same angle, as shown at 22 and 23. The sides of the cope and drag are provided all along their meeting edges with flanges 24 and 25, by which the sections of the flasks are held in position by means of pins 26. In Fig. 6 is shown a plan view of the drag, which consists of the bottom piece 20 and the end and side walls 27. Between the side walls are the bars or plates 28, having openings 29, while the end bar or plate 28 may be provided with longitudinal arms 30, which serve to sustain the sand at the open end of the flask. A bottom view of the cope is shown in Fig. 7, which consists of the end and side walls 31 and the bars or plates 32, having the openings 33 for the pattern, the combined shape and relative location of the openings of the flask being best shown in Figs. 4 and 5. The end plate 32 of the cope is provided with a plurality of arms 34 to sustain the sand in an obvious manner. The flask is conveniently held in position upon the base 3 of the frame, in close contact with the side pieces, by removable pins 35 entering openings 36 in the base-piece and engaging the outer end of the flask, as best shown in Figs. 1 and 8.

The operation is as follows: The pattern 14 is first secured to the pattern-support in a removable manner, conveniently by the screws 37, and the hub portion thereof projects through the opening at the inner end of the side pieces and forms a close joint therewith, it being understood that the movable projection 16 may or may not be used. The drag is then placed in position, with its angular end 21 fitting between the side pieces and held in such position with pins 35. The pattern extends into the drag and assumes the position seen in dotted lines in Fig. 6. The sand is packed within the drag and around the pattern, being inclosed by the side pieces 2 and the walls of the drag, while the parting is made from the upper edges of the sides and ends of the drag to the adjacent edges of the pattern—for instance, as shown in dotted lines in said Fig. 6. After this portion of the mold is formed the cope is placed in position, as shown in Figs. 1, 2, 4, and 5, and the sand packed therein to form the upper section of the mold, it being inclosed by the side pieces of the frame and the walls of the cope. After the mold is thus formed the pattern is unfastened from the pattern-support, so that it is free to move with the mold, and then the flask is moved outwardly a little distance upon the base 3 to remove the inner end of the hub portion of the pattern from the opening in the side pieces. The cope is removed and trimmed, after which the pattern can be removed from the drag and the latter trimmed. The pattern can then be used again to form another mold, and after four such have been formed they are placed in the position shown in Fig. 10 (only

the drags being shown for convenience) and a complete propeller can be cast.

The movable shutters or sections of the side pieces are useful even when the pattern-support is not shifted or adjustable, since it serves to make a close joint with the hub portion of the pattern at the correct angle, and in using this structure it is necessary, of course, to slide the shutters outwardly when the pattern is being inserted or when the pattern is to be removed with the mold.

The movable pattern support or plate is useful to adapt the device for use in connection with the patterns varying in size and shape. For instance, it may be desired to use a pattern in which the pitch of the plate will be such that it could not be passed through the openings in the flask, and to shift the pattern to cause it to fit within said openings it can be turned on its pivots 6^x, it being obvious that the nuts 13 are loosened to allow this movement. Upon reference to Fig. 9, however, it will be seen that the pattern shifts on the pivots 6^x as a center, so that the true center of the pattern is shifted to one side of the center of the molding device. To retain the pattern in its shifted position and to bring its center in line with the center of the molding device, the said pattern support or plate is moved laterally through the slotted connection of its sockets with the cross-pieces 4. The sockets are then tightened and the pattern held in its adjusted position by the fastening devices 11 and 13, as is obvious. The sections or shutters 16 and side pieces also come into use in this connection to cause the opening of the side pieces to conform to the position of the pattern-hub, the inner ends of said side pieces being built up or patched, if necessary. The pattern-support is held in its adjusted position until molds for the complete number of blades have been formed, it being noted that the pattern assumes the same relative position, and thus forms a regular and symmetrical mold.

Having thus described my invention, what I claim as new, and desire to secure by Letters Patent, is—

1. The combination of a frame having angularly-arranged upright side pieces meeting at their inner ends, an upright pattern-support situated adjacent to the junction of said side pieces, and a flask adapted to fit between said side pieces.
2. The combination of a frame having an upright pattern-support, angularly-arranged upright side pieces extending toward and meeting said pattern-support about midway between its ends, and a flask.
3. The combination of a frame having an upright pattern-support, angularly-arranged, upright side pieces having their inner ends

meeting adjacent to said support and provided with openings, and a flask adapted to fit between said side pieces.

4. The combination with a frame having an upright adjustable pattern-support, of a flask laterally situated relative thereto, and means for securing a pattern to said support to extend into said flask.

5. The combination with a frame having an upright laterally-adjustable pattern-support, of a flask laterally situated relative thereto, and means for securing a pattern to said support to extend into said flask.

6. The combination of a frame having an upright laterally-adjustable pattern-support adapted to swing, means for rigidly securing the same, and a flask laterally situated relative thereto.

7. The combination of a frame having a pattern-support carried by upright pivots mounted in laterally-adjustable sockets, means for rigidly securing the same, and a flask.

8. The combination of a frame having an upright pattern-support, adjustable, angularly-arranged, upright side pieces meeting said support at their inner ends, and a flask laterally situated relative to said pattern-support.

9. The combination of a frame having a pattern-support, side pieces having their inner ends notched or cut away between the upper and lower edges thereof to fit the top and bottom edges of the pattern, and a flask.

10. The combination of a frame having an upright pattern-support, angularly-arranged upright side pieces movable toward and away from said pattern-support and meeting at their inner ends adjacent to said support, and a flask laterally situated relative to said pattern-support.

11. The combination of a frame, having a pattern-support, angularly-arranged, upright side pieces movable longitudinally toward and away from said pattern-support and meeting at their inner ends adjacent to said support, and a flask laterally situated relative to said pattern-support.

12. The combination of a frame having a pivoted and laterally-adjustable pattern-support, means for holding the same rigid relative to the said frame, and angularly-arranged side pieces meeting midway between the sides of said pattern-support and provided with movable sections or shutters having their inner ends notched or cut away to fit the pattern, and a flask.

FREDERICK BALDT.
